UNITED STATES PATENT OFFICE.

SAUL SHALER, OF NEW YORK, N. Y., ASSIGNOR OF ONE-HALF TO ABRAHAM SHALER, OF NEW YORK, N. Y.

COMBINATION-PADLOCK.

1,314,431.

Specification of Letters Patent. Patented Aug. 26, 1919.

Application filed April 8, 1919. Serial No. 288,592.

To all whom it may concern:

Be it known that I, SAUL SHALER, a citizen of the United States, and a resident of the city of New York, borough of the Bronx, 5 in the county of Bronx and State of New York, have invented a new and Improved Combination-Padlock, of which the following is a full, clear, and exact description.

This invention relates to pad locks and 10 has particular reference to combination locks or such as may be manipulated without keys.

Among the objects of the invention is to provide a pad lock having a frame or body, 15 a removable shackle and a plurality of finger operated tumblers constituting the means for locking the shackle in the body, said tumblers being provided with index characters serving to establish the proper combination whereby the shackle may be removed 20 when the tumblers are set in a predetermined position.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had 25 to the accompanying drawings, in which like reference characters designate the same parts in the several views, and in which—

Figure 1 is a side elevation of my improved lock.

Fig. 2 is a vertical section of the same.

Fig. 3 is a perspective view of one of the heads.

Fig. 4 is a plan view of one of the body plates; and

Fig. 5 is a horizontal sectional detail on the line 5—5 of Fig. 2.

Referring now more specifically to the drawings I show my improved lock as comprising a body 10 including right and left heads 11 and 12 connected by means of any suitable upper and lower plates 13 and 14 respectively, adapted to be rigidly secured to the heads by any suitable means.

The heads may be made of any suitable metal or its equivalent and are tubular each having a vertical bore 17 of any suitable size or form in cross section being indicated as rectangular. The inner wall 18 of each head

or the wall constituting the face directed 55 toward the opposite head is preferably flat and smooth, while the opposite or outside wall 19 thereof is rounded although any other form may be substituted for the semi-cylindrical surface 19. Said inner wall 18 60 is provided with a pair of horizontal drill holes 20, the axes of which are in horizontal alinement with the corresponding holes of the opposite head. These holes are materially larger in diameter than the width of 65 the bores 17.

The bottom plate 14 is preferably solid or imperforate, while the upper plate 13 is provided with slots or holes 21 registering with the upper ends of the bores 17 and of 70 the same size and form.

The shackle 22 comprises a loop or bail 23 and a pair of parallel shanks or legs 24. The form or cross section of the shanks is substantially the same as that of the slots 21 75 and bores 17 into which the shanks are adapted to be projected for locking the shackle to the body. The bail portion of the shackle is provided with shoulders 25 or equivalent means to limit the movement of 80 the shanks into the body heads. When the shackle is inserted into the body and the shoulders 25 impinge against the upper plate 13, notches 26 formed along the inner edges of the shanks 24 lie in registry with 85 the holes 20, the vertical dimension or length of the notches being the same as the diameter of the holes 20.

The space between the upper and lower plates 13 and 14 and horizontally between 90 the two heads 11 and 12 is substantially filled by means of a plurality of pairs of tumblers 27 each of which comprises a preferably cylindrical portion, the inner end of which may be knurled at 27' while at its 95 outer end each tumbler has a central axial trunnion 28 fitted into a hole 20. Thus each of the tumblers at its trunnion has direct bearing in one of the heads, while at its end adjacent to the aligned tumbler of the same 100 pair has a dowel connection 29 with the other aligned tumbler. The dowel 29 is long enough to constitute a substantial support for the middle or adjacent end portions of 105 each pair of tumblers. The dowel may be rigidly connected to one of the tumblers and have loose engagement only with the other tumbler, or for convenience in assem-

blage the dowel may have movable connection in both of the sockets 30 which obviously must be in axial alinement with the trunnions. Each trunnion has a length corresponding to the space between the inner wall 18 of a head and the bottom of a notch 26 of the shank co-operating with such head. Furthermore each trunnion is provided with a notch or kerf 31, the depth of which longitudinally of the tumblers is substantially equal to the depth of a notch 26 and the width of which is substantially the same as the thickness of the shanks. The length of each of the kerfs 31 is parallel to the shanks and hence perpendicular to the axis of the tumblers.

From the foregoing specific description of the mechanism its mode of operation will be appreciated it is thought from the following summary: Each tumbler is provided with index characters 32 represented as the digit numerals, although they might be letters or numbers of a higher order. These index characters have reference to pointers 33 formed on one side of the heads opposite the several tumblers. The index characters are formed on the tumblers in any desired relation to the kerfs whereby any desired combination of the index characters may be provided for any individual lock. When the prescribed characters of a lock are adjusted in registry with the pointers 33 all of the kerfs will lie in the same plane, namely, the plane of the shackle shanks, thus setting the shackle free to be drawn from the body. When, however, any one or more of the tumblers are turned slightly from this opening position the shackle will be locked from removal due to the fact that at least one of the shoulders 34 just below the trunnions will strike against the cylindrical surface of any trunnions turned from the aforesaid opening position. Thus it will be seen that the shackle may be easily locked from removal and the opening of the lock may easily be effected by any one familiar with the combination of the particular lock. For any one unfamiliar with the combination the task of opening the lock is practically hopeless.

The device is simple and cheap of construction, easy of manipulation and strong and reliable in practice. Furthermore it is not liable to get out of order and cannot fail to provide for the direct removal of the shackle when the proper combination is observed.

The kerfs 31 may be formed in the ends of the trunnions 28 in any desired relation to the axes of the trunnions, but preferably I arrange the walls of the kerfs parallel to said axes and slightly off center as indicated in exaggerated degree by the centrally drawn dot and dash lines of Figs. 3 and 5. In other words while the kerfs are all adapt-

ed to occupy the same vertical plane and the shanks 24 of the shackle likewise lie in the same plane it follows that the holes 21 and the bores 17 must be similarly offset from the central plane of the lock. By this construction it follows that there can be but one opening position or adjustment of the several tumblers 27. In other words if the kerfs were central of the tumblers there might be two different opening positions or 75 adjustments of the tumblers, one position being the one intended and the other being the one 180 degrees remote therefrom.

I claim:

1. The herein described combination pad 80 lock comprising a body, a shackle having a shank projecting into the body, said shank having one or more notches formed therein providing shoulders, one or more tumblers journaled in the body in alinement with said 85 notches and movable around axes perpendicular to the axis of the shank, each tumbler having a trunnion projecting into a notch and having a kerf adapted to register with the notched portion of the shackle shank 90 whereby when the tumblers are turned to a predetermined position with respect to the body of the shackle the shoulders aforesaid will not engage the trunnions.

2. In a pad lock, the combination of a 95 body having oppositely arranged spaced heads, the opposing faces of which are formed with axially alined pairs of bearing holes, a shackle having a pair of parallel shanks projectable into said heads and intersecting the axes of said holes, each shank having notches registering with the holes aforesaid, and tumbler means journaled in the space between the heads and having end trunnions bearing constantly in the axially 105 alined holes, the outer ends of the trunnions being provided with kerfs along which the shanks may slide when the tumbler means are properly positioned.

3. In a pad lock, the combination with a 110 body having oppositely spaced heads having axially alined bearing holes, the heads being provided with bores perpendicular to the axes of said holes, a shackle having shanks 115 slideable into said bores and having notches registering with the axially alined holes, and tumbler means journaled in said holes, the parts of the tumbler means in the holes being larger in diameter than the thickness of the shanks and projecting into the shank notches 120 for locking the shanks in the bores aforesaid, said projecting parts of the tumbler means having kerfs which when alined with the shanks permit the withdrawal of the shackle, substantially as set forth.

4. The combination of a body having spaced parallel heads formed on their inner opposing faces with axially alined bearing holes, said heads having bores the axes of which lie in the same plane as the axes of the 130

holes, but perpendicular thereto, a shackle having shanks projectable into the bores and having notches registering with the holes aforesaid, the shanks being narrower than 5 the diameter of the holes, a pair of tumblers having opposite end trunnions journaled in said holes, and means connecting the adja-

cent ends of the tumblers for mutual support and providing for independent rotation of the tumblers, said trunnions having kerfs 10 to permit the withdrawal of the shackle, substantially as set forth.

SAUL SHALER.
